US0D1017720S

(12) **United States Design Patent** (10) **Patent No.:** **US D1,017,720 S**
(45) **Date of Patent:** **** Mar. 12, 2024**

(54) **COLOR AND SHAPE SORTING BOX**

(71) Applicant: **Ruirong Zhou**, Chaozhou (CN)

(72) Inventor: **Ruirong Zhou**, Chaozhou (CN)

(**) Term: **15 Years**

(21) Appl. No.: **29/903,704**

(22) Filed: **Sep. 27, 2023**

(51) **LOC (14) Cl.** **21-01**

(52) **U.S. Cl.**

USPC **D21/470; D21/468; D19/59**

(58) **Field of Classification Search**

USPC ..... D21/303, 336, 337, 499, 338, 341, 342, D21/310, 311, 300, 362, 385, 386, 388, D21/389, 393, 398, 399, 401, 404, 405, D21/455, 456, 468, 470, 471, 473, 474, D21/475, 476, 478, 479, 483-488, 506, D21/507, 510, 589, 789, 790, 796, 811, D21/812, 821, 826, 830, 360, 349, 301, D21/302, 469; 273/336, 337, 376, 398, 273/401, 407, 110, 112, 113, 118 R, 273/123 R, 236, 241, 248, 249, 280, 289, 273/290, 153 R-156, 153 P, 153 S, 447, 273/449, 450, 459, 142 HA, 271, 242, 273/281, 282.1-282.3, 283-288, 264, 273/344, 276, 272, 267, 261, 309, 260, 273/239, 244, 161, 429, 157 R, 146, 273, 273/277, 145 C, 440; 446/69, 71, 75, 76, 446/81, 85, 87, 117, 118, 124, 125, 127, 446/236, 248, 249, 251, 252, 265, 396, 446/476, 486, 487, 489, 491, 901, 1, 5, 8, 446/10, 13, 91, 227, 310; 434/208, 259, 434/433, 258, 334, 81, 128, 236, 345, 434/347, 365, 367, 368, 393, 402, 403, 434/429, 430; D7/610, 558; 108/94, 108/101, 92, 42; 211/188; 463/10, 9, 48, 463/49; D6/678.1, 675.1; 84/470 R, 476;

(57) **CLAIM**

The ornamental design for a color and shape sorting box, as shown and described.

DESCRIPTION

FIG. 1 is a top perspective view of a color and shape sorting box showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view of a color and shape sorting box in another configuration of use; and,

FIG. 9 is an exploded top perspective view thereof.

The broken lines in the drawings depict portions of the color and shape sorting box that form no part of the claimed design.

1 Claim, 6 Drawing Sheets
